UNITED STATES PATENT OFFICE.

WILLIAM M. BARKER, OF CANTON, OHIO.

DRIER.

Application filed July 31, 1924. Serial No. 729,301.

The invention relates to drying apparatus for removing excess moisture from coal and other materials by means of heated gases; and the object of the improvement is to cause the wet material to flow continuously, in a uniform attenuated stream, through a current of the drying gas.

In drying apparatus of this kind it is difficult to bring every particle of coal into direct contact with drying gases; and for the purpose of bringing every particle of material several times into direct contact with a current of hot gas, the present invention involves the use of a series of superposed conical funnel chutes, a series of rotating disks therein for distributing the material centrifugally from the periphery of the disks to annular walls at the upper ends of the chutes, so that the material is spread out and caused to fall through a current of drying gas circulated through and around the funnel chutes.

The improved apparatus is well adapted for drying lump or slack coal, as a preliminary step for a grinding or pulverizing operation, and the invention is illustrated and described with reference to such a use, without intending to limit it thereto; and in the accompanying drawings, forming part hereof, the figure is an axial elevation section of a centrifugal drier embodying the invention.

Upon a cylindrical case 1 is mounted a feed hopper 2 for feeding wet coal into the top of the case and a centrifugal fan 3 for exhausting drying gases therefrom, there being a drying gas inlet 4 at or near the bottom of the case.

To the top wall 1' of the case is secured a depending annular wall 5, below which is secured a funnel hopper 6; and below the same, in the middle portion of the case, is secured a second depending annular wall 5^a, below which is secured a second funnel hopper 6^a.

The upper end 6' of the upper funnel chute is preferably secured directly to the wall of the casing, so as to leave an annular opening 7 between the top of the funnel and the bottom of the annular wall 5, leading into the annular chamber 8 between the depending wall 5 and the wall of the case 1, and the upper end 6^a the lower funnel hopper is preferably secured directly to the bottom of the lower annular wall 5^a, which in turn depends from a horizontal ring partition 9 secured to the peripheral wall of the

case and is provided with a plurality of ports 9' between the annular wall 5^a and the peripheral wall of the case; the ring partition being located around the lower end of the upper funnel hopper 6 so as to form an annular opening 10 around the same.

In the bottom wall 1'' of the case is mounted a discharge hopper 11, the upper funnel 11' of which surrounds the lower end of the funnel hopper 6^a, with an intervening annular opening 12; and the lower outlet end 11'' of the discharge hopper is provided with a pendent gate 13, which is preferably counterbalanced by a weight 14 for normally holding it closed.

A vertical shaft 15 in the axis of the case is mounted in bearings 16 and 17 at the top and bottom thereof, and upon this shaft, within each annular depending wall 5 and 5^a is secured a horizontal disk table 18 or 18^a having a peripheral diameter considerably less than the diameter of the wall, so as to leave an annular interval a substantial width between the periphery of the disk and the adjacent annular wall.

The shaft 15 may be operated by a worm gearing 19 through a speed reducer 20 and a chain gearing 21 by a motor 22, and the centrifugal fan 3 may be operated through the chain gearing 21; and these parts may be arranged for turning the axial shaft some 50 R. P. M. for distributing the coal, and the centrifugal fan some 846 R. P. M. for exhausting some 3290 cubic feet of air per minute from an apparatus having a case some six feet in diameter, for drying some ten tons of coal per hour from an eight per cent moisture to about a two per cent moisture.

The feed hopper 2 is provided with a feed gate 2' for controlling the admission of wet coal into the apparatus, and the same is located so as to deliver wet coal upon the upper rotating disk 18.

In the operation of the machine, the rotation of the upper disk 18 spreads the wet coal and distributes the same by centrifugal force directly outward against the adjacent annular depending wall 5, whence it falls directly downward in a thin cylindric stream upon the conically converging wall of the upper funnel 6, by which it is discharged on to the lower rotating disk 18^a.

The rotation of the lower disk again distributes the coal centrifugally and throws the same directly outward in an attenuated

2
mushroom stream against the adjacent annular depending wall 5^a, whence it drops downward in a thin cylindric stream onto and along the conically converging wall of 5 the lower hopper 6^a, whence it is delivered in a thin cylindric stream into the discharge hopper 11, and when a sufficient amount of coal is accumulated therein to overbalance the outlet gate 2' the coal flows outward 10 through the outlet.

The gas inlet 4 is connected with any suitable source of supply, which may be hot flue gas from a boiler or other furnace, and the operation of the exhaust fan 3 circulates the 15 same through the apparatus as indicated by arrows in the drawing, somewhat as follows: A portion of the hot gas flows through the annular openings 12 between the bottom of the lower funnel and the top of the discharge 20 hopper, so as to pass through the descending cylindric stream dropping downward from the funnel; whence the same gases flow upward through the lower funnel along the stream of coal sliding 25 downward upon the wall thereof, and thence upward through the thin stream of coal flowing outward from the rotary disk and thence converging into the lower end of the upper funnel hopper.

30 Suitable valves 23 are provided for the openings 8' in the ring partition 9 so as to divide the hot gases entering through the inlet opening 4 into another portion which flows upward around the wall of the funnel 35 hopper and into and around the wall of the upper hopper; whence this portion of the hot gases flows inward and joins the other portion which flows upward through the lower hopper into the lower end of the upper 40 hopper; whence the recombined hot gases flow upward and outward along the stream of coal flowing downward upon the bottom of the hopper and the attenuated cylindric stream of coal falling down from 45 the upper annular depending wall; and thence upward into and around the annular channel 8 around the same to the inlet 24 of the exhaust fan 3.

50 During the progress of the hot gases through the coal, they not only flow along through the streams of coal moving downward through the converging walls of the two funnels, but they also pass four times through an attenuated stream of coal as it 55 drops downward in cylindric streams into and out of the upper funnel, as it is thrown outward in a mushroom stream from the pe-

riphery of the lower rotary disk, and as it drops downward in a cylindric stream from the lower funnel. Furthermore the flow of 60 hot gases against the outside of the funnel walls, and through the ports 9' of the horizontal ring partition 9 heats both sides of the funnel walls so that they in turn heat and dry the coal sliding downward along 65 the inside thereof.

By these means all the particles of the fed-in raw coal which may adhere or stick to each other are broken apart by the impinging centrifugal action of the mushroom 70 streams against the annular walls, there is no place in the apparatus where the separated particle can accumulate or lodge in any considerable mass or quantity; so that every particle of the coal is brought into 75 direct contact with the ascending hot gases, several times during its tortuous passage in attenuated streams through the apparatus; and very little power is required to rotate the disks for spreading the coal and 80 operating the fan for circulating the hot gases.

I claim:

1. Material drying apparatus including a 85 rotating disk, an annular wall spaced from the periphery of the disk, a funnel spaced from the annular wall, and means moving drying gas through the annular interval between the funnel and the annular wall.

2. Material drying apparatus including 90 an annular wall, a funnel for converging a cylindric stream of material downward upon the inside of the funnel, and means moving hot gas against the outside of the funnel and through the annular interval between the funnel and the annular wall. 95

3. Material drying apparatus including a series of rotating disks, one above the other, funnels for receiving material distributed centrifugally by the disks, an external annular wall spaced from the funnels and the disks, and means moving drying air around the inside and outside of the funnels and through the intervals between the funnels and the disks. 100

4. Material drying apparatus including a funnel, an external annular wall around the funnel, a ring partition between the funnel and the external annular wall, and valve apertures in the ring. 110

In testimony that I claim the above I have hereunto subscribed my name.

WILLIAM M. BARKER.
